UNITED STATES PATENT OFFICE.

ANDOR DE HERTELENDY, OF WASHINGTON, DISTRICT OF COLUMBIA.

RATCHET WRENCH.

Application filed August 9, 1926. Serial No. 128,216.

The object of this invention is to provide a wrench with reversible ratchet mechanism and with independently adjustable jaw members, eccentrically mounted, and adapted for movement to various positions, for obtaining a large number of adjustments in order to fit nuts of different standard sizes. A further object is to effect this result by providing a jaw mounting device having reversible ratchet mechanism associated therewith and eccentric elements of different sizes, constituting working faces, these elements being retained in the special manner indicated below.

A further object is to provide for varying the effective size of either jaw member by the use of detachable means which may be applied in order to meet particular requirements. With the foregoing and other objects in view, the invention consists in the novel construction and arrangement of elements described, illustrated and claimed, it being understood that modifications may be made within the scope of the claims without departing from the spirit of the invention.

In the drawings forming part of this application,

Fig. 1 may be considered as a plan view of the wrench.

Fig. 2 is a plan view showing the adjustable elements of the jaws in another position, for use on a very much smaller nut than that shown in Fig. 1,—this view illustrating the jaw mounting devices detached.

Fig. 3 is a view of the lower element of the structure receiving the jaw mounting means of Fig. 2.

Fig. 4 is a section on line 4—4 of Fig. 1.

Fig. 5 is a section on line 5—5 of Fig. 1.

Fig. 6 is a view showing in perspective detached portions of the structure of Fig. 2, and showing the manner in which the adjacent end portions of these elements are formed, permitting of assembly in order to produce the structure of Figs. 1 and 2.

Fig. 7 is an end elevation of the adjustable element, or jaw face, shown in the upper part of Figs. 1 and 2.

Fig. 8 is a similar view of the other adjustable element or jaw face.

Fig. 9 is a perspective view of a channel element which may be applied to one or both of the movable jaw faces, in order to afford

additional adjustment, and increase the scope or number of the changes in adjustment made possible, in order to accommodate the wrench to different nuts.

The main portion of the wrench comprises a two-part housing, and one part, which will be termed the upper portion or cover portion, for convenience, is designated 10,—or that portion comprising a part of the handle is so designated, and formed therewith is a partly circular portion 11 adapted to cooperate with a corresponding portion 12 formed integrally with the portion 13 of the handle which cooperates with element 10, in forming the complete handle. The portions 11 and 12 each form approximately three-fourths of a circle, as the structure is illustrated in the drawings, and portion 12 is provided with an annular shoulder 14 adapted to receive the disk or jaw mounting device 15 of Fig. 2, the cover portion 11 retaining element 15 in contact with the shoulder just referred to, but permitting rotary movement.

Element 15 is provided with a series of teeth 16, and these teeth are engaged by a dog 17 carried by a rotatable disk 18 suitably mounted between the elements of the housing and adapted to be partly rotated by thumb member 19.

Disk 18 carries a lug 18', and a forked resilient device including the diverging members 20 and 21 is mounted within the housing, and the diverging portions cooperate with lug 18', one of these portions at a time serving to retain the dog 17 in yielding engagement with the teeth 16. The disk 18 may be shifted by thumb member 19 on the outer side of the housing, and rotated thru the greater portion of a circle, in order to engage the teeth from the opposite side. The lug 18' would then be in engagement with resilient member 21, whereas in Fig. 1 it is shown as being in engagement with member 20. This arrangement permits of the use of the tool as a ratchet wrench, operating in either direction, depending upon the position of the dog 17 and the mounting means therefor.

The element 15 mounts jaws 25 and 26, and a segmental element 27 provided with teeth 16' is adapted to fill the segmental opening shown in the element 15. The adjustable jaws, or working faces, 25 and 26 are sup-

ported by trunnions 25' and 26', and these trunnions at one end of each jaw are mounted in bearings in element 15. The opposite ends of the adjustable jaws carry trunnions 6 each provided with slots extending at an angle with reference to each other, these trunnions at the left of Fig. 2, and further shown in Figures 6, 7 and 8, being designated 28. The trunnions are eccentric with 10 reference to the main axes of each of the adjustable jaws 25 and 26, and each of these jaws may be rotated thru a quarter turn, and retained in that position.

The jaws 25 and 26 shown respectively in 15 Figures 7 and 8 are of the relative proportions there illustrated, and since each element 25 and 26 may be rotated thru a quarter turn with reference to each side of the other jaw, the eccentric mounting of the jaws permits of four different adjustments between 20 element 25 and each side of element 26, in order to provide four different positions by the adjustment of one jaw.

As the other jaw may likewise be rotated 25 and similarly adjusted, a total of sixteen adjustments may be obtained in this manner, that is, a nut of the maximum size illustrated in Fig. 1, may be controlled, or a nut of the size shown in Fig. 2 may be similarly controlled by a different adjustment, and nuts 30 of varying sizes between these extremes (or sixteen sizes in all) may be handled by the wrench, without further adjustment or provision therefor. However, the channel element 30 of Fig. 9 may be employed in connection with either or both jaws, and additional adjustments may be provided by applying the channel element to the face of the jaw or jaws. Moreover, elements 30 of 40 different thicknesses may be provided.

In order to maintain an adjusted position of the jaws, the segmental element 27 is provided with a tongue 32 adapted to engage any of the slots 33 of the element 28. Lugs 45 34 cooperate with the recessed portions 35 in the end walls of the shoulders 15'; and a close fit is here provided, the trunnions 28 being received by the bearings 36, and being rotatable in these bearings until locked by the inward movement of segmental element 27 causing the tongues 32 and lug 34 to engage as indicated. The element 15 constituting a jaw mounting device, and the segmental member 27 applied thereto, form a structure 50 rotatable in the socket produced by elements 11 and 12 of the housing.

Having described the invention what is claimed is:—

1. In a wrench, jaw mounting means, a plurality of eccentrically mounted jaws, angular in cross-section, and carried by said means, and detachable means providing a segmental bridging element between the outer ends of the jaws, for retaining the jaws in an adjusted position. 65

2. In a wrench, jaw mounting means, a plurality of eccentrically mounted jaws, angular in cross-section, and carried by said means, and a detachable segmental bridging element, forming with an element of the 70 mounting means a circular rotatable device.

3. In a wrench, jaw mounting means including ratchet mechanism, and a plurality of eccentrically mounted jaws carried by said means, the jaws including trunnions by 75 which they are rotatably mounted, and means bridging the jaws, and engaging one of the trunnions of each jaw for retaining the jaws in an adjusted position.

4. In a wrench, jaw mounting means comprising a segmental element and a detachable bridging element of segmental form, an eccentrically mounted jaw carried by the mounting means, said jaw being angular in cross-section, means for retaining the jaw in 80 a fixed position, and a second jaw opposite that first named and engaged by the bridging element.

5. In a wrench, jaw mounting means of segmental form, and a second element of 90 segmental form complementary to that first named, for completing an annular structure, said structure having teeth formed exteriorly thereof, means for engaging the teeth, an eccentrically mounted jaw carried by the 95 mounting means, said jaw being angular in cross-section, means for retaining the jaw in a fixed position, a second jaw opposite that first named, and a detachable device for varying the effective size of the eccentrically 100 mounted jaw.

6. In a wrench, jaw mounting means including a plurality of complementary segmental elements and ratchet mechanism, said elements constituting a rotatable device, and spaced jaws carried by one of the segmental elements, the other of said segmental elements bridging the space between corresponding ends of the jaws. 105

In testimony whereof I affix my signature.

ANDOR DE HERTELENDY.
